[57] **CLAIM**

The ornamental design for a bird feeder, as shown and described.

DESCRIPTION

FIG. 1 is a perspective view of a bird feeder showing my new design;
FIG. 2 is a side elevational view thereof;
FIG. 3 is a top plan view thereof;
FIG. 4 is a bottom plan view thereof; and
FIG. 5 is another perspective view thereof, showing the cover in a tilted position.

FIG. 1

FIG. 2

FIG. 3

FIG. 5

FIG. 4
